FIG. 1

FIG. 2

FIG. 3

FIG. 4

FIG. 5

George W. Cary,
INVENTOR.

BY

Frank A. Cutler,
ATTORNEY.

UNITED STATES PATENT OFFICE.

GEORGE W. CARY, OF GREENFIELD, MASSACHUSETTS, ASSIGNOR TO GOODELL MANUFACTURING COMPANY, OF GREENFIELD, MASSACHUSETTS, A CORPORATION OF MASSACHUSETTS.

MITER BOX.

Application filed January 27, 1923. Serial No. 615,199.

To all whom it may concern:

Be it known that I, GEORGE W. CARY, a citizen of the United States of America, and a resident of Greenfield, in the county 5 of Franklin and State of Massachusetts, have invented certain Improvements in Miter Boxes, of which the following is a specification.

My invention relates to improvements in 10 miter boxes, and more particularly to certain attachments therefor, and consists of an angle attachment adapted to be secured to the bed of a miter box at one end, a length-gauge attachment adapted to be secured 15 to said bed at the other end, and a "square" scale delineated on or attached to the front side of the arcuate member of said bed in front, such parts and members being of new and novel construction 20 and forming new and novel combinations, all as hereinafter set forth.

One object of my invention is to provide 25 a miter box with comparatively simple and inexpensive, yet strong and durable, and convenient attachments or devices, wherewith may be obtained adjustments for angles more acute than 45°, on the one hand, and is facilitated the cutting of duplicate 30 parts of any length within the range of adjustment of the length gauge, on the other hand. The angle attachment may also serve as a molding holder, and used in connection with the length gauge.

It is ordinary practice for a carpenter 35 to determine angles for cutting rafters or finish with a carpenter's steel square, and another object of my invention is to provide a miter box with means whereby rafters or finish can be cut at the desired angle 40 without the aid of a square, or recourse to the degree scale of the miter box.

Other objects and advantages will appear in the course of the following description.

45 I attain the objects and secure the advantages of my invention by the means illustrated in the accompanying drawings, in which—

Figure 1 is a top plan of the principal 50 parts of a miter box with which my attachments in preferred form are combined; Fig. 2, a front elevation of the "square" scale showing the same straightened out; Fig. 3, an enlarged, rear end elevation, with parts 55 broken out, of the angle attachment; Fig.

4, an enlarged, front end and elevation of the length-gauge attachment, and Fig. 5, a right-hand side elevation, in partial section, of said last-named attachment.

Similar reference characters designate 60 similar parts throughout the several views.

In the first view I have shown the principal parts of a miter box, substantially like that covered by Letters Patent of the United States, No. 978,576, and will first 65 briefly describe the same. A bed comprising a frame 1 and plates 2—2 and provided with legs or feet 3, there being the usual open quadrant 4 between adjacent edges of said plates, vertical back members 5—5 spaced apart to leave a vertical opening for the saw, a radius bar 6 pivotally connected at 7 with said frame, and extending beneath said frame and beyond the front 70 and back sides thereof, a channel bar 8 supported from said radius bar in the opening (4), and vertical saw guides or posts 9—9 rising from said radius bar adjacent to opposite ends thereof. Means (not shown) are provided for locking the radius bar 6 75 at any desired angle relative to the frame, whereby a board or other piece of stock may be sawed at a right-angle or at an acute or obtuse angle to its length, the saw (not shown) being operated through vertical 80 slots in the posts 9 and the aforesaid space or opening between adjacent ends of the back members 5, and finally coming down 85 into the channel in the bar 8, all in the usual and well-known manner. The sides 90 of the opening 4, which latter is bounded by the adjacent ends of the plates 2, form a right-angle, and the front of said opening is bounded by an arcuate part 10 of the frame 1, and a degree scale 11 is provided on said arcuate part, such scale being common to miter boxes. The scale 11 is provided to enable the radius bar 6 to be set at any angle within the available quadrant of adjustment. 95

Secured by means of two bolts 12 to each 100 end of the frame 1 is a support and guide in the form of a bar 13. The bars 13 are alike and interchangeable. In the top of each bar 13 extending longitudinally thereof is an angular slot, channel, or groove 14. Along one side of the groove 14 is an overhang 15. Thus it is seen that the groove 14 in cross section has two wide sides 105 below and one narrow side above. The angles 110

formed by the aforesaid wide and narrow sides are right-angles, and in reality constitute three angles of a square. One of the wide sides of the groove 14 forms an acute angle with the side of the bar 13 which is contiguous with the frame 1, and the narrow side of said groove forms an acute angle with the top of said bar. The bolts 12 pass through lateral openings 16—16 10 in each bar 13 and are tapped into the frame 1. An opening 17 is tapped into each bar from the outer face thereof and extends beneath the groove 14 in said bar. The opening 17 is located midway between the ends 15 of the bar 13. A thumb-screw 18 is provided to fit the opening 17 in each bar 13.

A slide 19 is provided to fit the groove 14, such slide being square in cross section, except adjacent to its rear terminal where said bar is flattened, and a post 20 is mounted 20 on such flattened part.

A clamp 21 is mounted on each thumb-screw 18, and such clamp in each case consists of an approximately vertical plate 25 having an inwardly-extending lip 22 at the bottom, to engage the under side of the associated bar 13, and an inwardly- and upwardly-extending lip 23 to engage the inclined side of the slide 19, or of a similar 30 slide 24, which side extends upwardly and inwardly from the outer longitudinal edge of the horizontal, central plane of such slide. Thus it is seen that, when either thumb-screw 18 is tightened, the clamp 21 mounted thereon is forced inwardly toward 35 and against the contiguous bar 13, and into wedging engagement with the slide 19 (or 24) carried by said bar, thereby causing said slide to engage frictionally said bar with sufficient force to hold the former against 40 longitudinal movement. Upon loosening the thumb-screw 18 the slide 19 (or 24) can be moved freely lengthwise in either direction.

45 The groove 14 is located off center longitudinally in each bar 13, consequently the slide 19 (or 24) extends beyond the bar 13 on the side of the latter where the associated clamp 21 is located, with the result that, 50 when said clamp is forced inwardly by its thumb-screw 18, said clamp forces the slide downwardly and inwardly, thus securing a binding effect on all four sides of the slide.

The slide 24 is provided at the rear terminal with a block 25 in which there is a transverse slot 26 to receive a horizontal length gauge 27. The length gauge 27 is merely a bar which is rectangular in cross section, and has its inner terminal bent forwardly at right-angles to the main portion of said bar. The thickness of the gauge 27 is slightly greater than the depth of the slot 26, which causes the top of said gauge to be located above the top of the block 25. 65 Tapped into the block 25, behind the gauge

27 and extending downwardly into the slide 24, is a screw 28 which is provided with a handle 29. Interposed between the head of the screw 28 and the top of the block 25 is a washer 30, such washer having a sufficiently large diameter to enable the same to bear on the gauge 27. Upon tightening the screw 29 the washer 30 is caused forcibly to engage the gauge 27 and to hold the same against longitudinal movement. Upon 70 loosening the screw 28 the gauge 27 can be adjusted longitudinally to whatever extent required.

The slide 24, like the slide 19, is square in cross section, fits the groove 14 in either bar 80 13, and is adjusted and secured therein after adjustment by means of the associated thumb-screw 18 and clamp 21, in a similar manner to that in which said slide 19 is adjusted and secured as hereinbefore explained.

If it be desired to make a cut at an angle that is too acute to be available with the miter box proper, the slide 19 is adjusted to whatever extent may be necessary to locate the post 20 in position to compensate for the difference between the normally available 45° angle and the desired angle, and then the stock to be cut is placed on the plates 2 against the outer end of the right-hand back member 5 and the front side of the post 20, and held in such position while being cut, the saw-guide member having been previously adjusted or moved into the required position.

The process of cutting moldings or the like may frequently be facilitated by using the angle gauge. To this end the slide 19 is adjusted in such a manner as to locate the post 20 in advance of the vertical plane of the front or face of the back members 5 a distance equal to the major lateral dimension of the stock. Then the stock is placed on the plates 2 against the back members 5 and behind the post 20 and cut, said post assisting materially in holding said stock in place during the cutting operation.

The length gauge 27 is employed for cutting duplicate parts, and said gauge is adjusted to locate the inner terminal of the same in proper position for fixing or determining the length of the stock to be cut, by moving said gauge longitudinally in the block 25. The gauge 27 is properly located relative to the thickness or width of the stock to be cut by adjusting the slide 24 in its bar 13. The stock is placed on the plates 2 against the back members 5 and moved into contact with the bent terminal of the gauge 27, and there held while being cut. The angle gauge post 20 may frequently be employed to advantage in connection with the length gauge, to assist in holding the stock in place while being cut.

The slides 19 and 24, with the parts and

members supported and carried thereby, can be removed at any time from the bars 13 and laid one side out of the way, and said slides can be as readily returned to place in 5 said bars. Thus it is not necessary to be to the trouble of removing the supports 13, or either of them, whenever it is desired to lay aside the angle gauge attachment and the length gauge attachment, or either of 10 them. With these attachments I am able to obtain with practically no difficulty the most minute adjustments, and there is provision therein for obtaining such adjustments easily, quickly, and conveniently, while at 15 the same time the locking elements are safe and secure.

A scale 31 is secured to the front side of the arcuate part 10 of the frame 1, and this scale is so graduated and marked, from zero 20 in the center to twelve at each end, that the same can be used in place of the scale 11 as a means of determining the location of the saw-guide members, when it is desired to cut such stock as roof rafters which ordinarily 25 have to be laid out with the aid of a carpenter's steel square. In using the steel square it is necessary to indicate on the rafters two points, from the arms of said square, as "12" and "6" for example, and then 30 to connect the points with a line to serve as a guide for the saw; while with the scale 31 it is simply necessary to set the saw-guide members on the numeral which determines the angle of the cut required, and proceed to 35 place the rafter in position and cut through the same. The numerals "1" to "12," inclusive, denote or indicate what are technically termed "one cut," "two cut," "three cut," etc. When the saw-guide members are 40 set on "0" on the scale 31 the saw cuts at an angle of 90° , and when said members are set on either "12" on said scale the saw cuts the stock at an angle of 45° . This last is termed a "twelve cut." The other numerals 45 on the "square" scale correspond with rafter angles between 45° and 90° .

More or less change in the shape, size, construction, and arrangement, of some or all of the parts of this invention, may be 50 made without departing from the spirit of the same, or exceeding the scope of what is claimed.

What I claim as my invention, and desire to secure by Letters Patent, is—

55 1. The combination, in an attachment for a miter box, with a bar attachable to a miter-box bed, said bar having a longitudinal

groove therein which opens through one side and is partially formed by an undercut adjacent to the other side thereof, said groove 60 in cross-section having an angle in the bottom and an angle formed in part by the undercut portion, of a slide angular in cross section to fit said groove with one angular part of said slide in the bottom of said 65 groove, another angular part beneath said undercut portion, and another angular part extending beyond said bar, said slide being provided with a work-engaging member, a screw-threaded member tapped into said 70 bar, and a clamp mounted on said member and having a lip which extends beneath said bar and a lip which extends into engagement with said last named angular part of said slide. 75

2. The combination, in an attachment for a miter box, with a bar attachable to a miter-box bed, said bar having a longitudinal groove therein which opens through one side and is partially formed by an undercut adjacent to the other side thereof, said groove 80 in cross-section having an angle in the bottom and an angle formed in part by the undercut portion, of a slide angular in cross section to fit said groove with one angular 85 part of said slide in the bottom of said groove, another angular part beneath said undercut portion, and another angular part extending beyond said bar, a longitudinally-movable length gauge carried by said slide, 90 means also carried by said slide to clamp said gauge and hold the same against longitudinal movement, a screw-threaded member tapped into said bar, and a clamp mounted on said member and having a lip which extends beneath said bar and a lip which extends into engagement with said last named angular part of said slide. 95

3. The combination, in a miter box, with a bed, and grooved bars adapted to be attached outside to the ends of said bed, of slides receivable in the grooves in said bars, movable means to clamp said slides to said bars, a post carried by one of said slides, and length-gauge clamping means carried by the other of said slides, said slides being adapted to be lifted out of said grooves and interchanged, when said clamping means is removed. 100 105
